UNITED STATES PATENT OFFICE.

ALBIN K. LONGREN, OF KANSAS CITY, MISSOURI.

TURNUCKLE.

1,321,113.

Specification of Letters Patent. Patented Nov. 11, 1919.

Application filed January 31, 1918. Serial No. 214,626.

To all whom it may concern:

Be it known that I, ALBIN K. LONGREN, a citizen of the United States, residing at Kansas City, in the county of Jackson and State of Missouri, have invented certain new and useful Improvements in Turnbuckles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to turnbuckles, and more particularly to a turnbuckle lock; the principal object of the invention being to provide simple and effective means which may be easily applied to or removed from the turnbuckle, and which will effectively prevent any possible turning or loosening of the turnbuckle while it is serving in its functional capacity.

A further object of the invention is to provide a lock of this character, particularly applicable to that type of turnbuckle used in aeroplanes, or the like, for tightening or adjusting the frame or wing wires.

In accomplishing these objects, I have provided improved details of structure, the preferred forms of which are illustrated in the accompanying drawings, wherein:

Figure I is a side view of a turnbuckle having a locking member constructed according to the present invention applied thereto.

Fig. II is a longitudinal, sectional view of the same, particularly showing the application of the locking member to the screw stems.

Fig. III is a view of the locking member removed from the turnbuckle.

Referring more in detail to the drawings: 1 designates a turnbuckle to which the

present lock is particularly applicable, and which comprises a barrel or body portion 2, whereinto the opposite end stems 3 and 4 are threaded respectively by right and left hand threads, and are adapted to move, when the device is in operation, simultaneously into or from the barrel by revoluble movement of the latter.

In order that the device may be attached in functional position to the frame or to the ends of cables, or wires, to be connected or tightened thereby, I provide the outer end

of the stem 4 with an eye 5 adapted to receive the end of a cable 6, and the end of the stem 3 with a yoke head 7 comprising spaced wings 8-8', through which a bolt 9 is extended to anchor that end of the turnbuckle to a link 10 whereby the same is fixed to a suitable anchorage. In the present instance, the cable 6 is attached by extending the end thereof through the eye and turning the same back along the cable and the lapping portions wound with fine wire. This connection, however, is not essential to the use of the turnbuckle, nor is it essential that one stem be provided with a yoke and the other with the eye, but both stems may comprise an eye, or a yoke portion, without preventing the use of the locking member, presently described.

With the turnbuckle so arranged and the cable 6 and link 10 attached thereto, it is apparent that turning of the barrel 2 in one direction will move both stems inwardly, and by turning the same in the opposite direction both stems will move outwardly, and in order that the stem and body parts may be locked when adjusted to a certain position, to prevent any possible turning of the parts which might allow members connected thereby to be loosened, I have provided a locking means, the same comprising a single piece of wire 12 of substantial strength and stiffness to effectively serve its purpose, and which is bent at one end to form a hook 13, and at its opposite end has a portion 14 turned laterally therefrom in the same plane with the hook 13.

After the stem members have been properly adjusted in the barrel 2 they may be locked in this position by the wire 12 by inserting its hooked end 13 within the eye 5 of the stem 3 and extending the laterally turned end portion between the ears of the yoke head 7. To prevent displacement of the wire from this position, I provide an anchoring means, comprising a cotter key 15 which is removably fixed within the barrel by extending the same through alining apertures 16-16' located centrally in the barrel and between the inner ends of the stems 3-4, and which has an eye 17 at one end through which the wire 12 is extended and thereby retained against the side of the barrel, and the ends thereof retained in locking position within the eye and yoke members.

With the parts so constructed, and the

cables attached thereto, in using the turnbuckle, the cables are first adjusted to a desired tension by turning the barrel 2. The lock wire 12 with a cotter key 15, located thereon is then applied by inserting the hook 13 within the eye 5, and extending the key 15 through barrel apertures and the end portion 14 of the wire between the yoke wings 8—8'. The ends of the cotter key 15 are then bent along the barrel to retain the key, and the latter retains the lock wire in position along the barrel and all are thereby locked against any possible revoluble movement.

15 To remove the locking device it is only necessary to straighten the ends of the cotter key sufficiently that it may be removed from the barrel, and the ends of the wire removed from the eye and yoke members. The parts are then free and may be adjusted as desired.

20 It is apparent that a device of this character is simple in operation, substantial, may be provided at a small cost, and may be easily and quickly applied or removed when adjustment is necessary, and as adjustment of such parts seldom varies more than one half turn of the stems, it is apparent that the same lock wire may be used for a number of adjustments of the parts between certain limits.

30 Having thus described my invention, what I claim as new therein, and desire to secure by Letters-Patent, is:—

1. In combination with a turnbuckle comprising a central barrel and screw stems threaded into opposite ends thereof, of a locking member having end portions applicable to the stems in locking relation, and means for fixing the member to the barrel to prevent any relative rotation of the turnbuckle parts.

2. In combination with a turnbuckle comprising a connecting barrel, screw stems threaded into opposite ends of said barrel having openings therethrough at their outer ends, a locking member extending along said body and having portions turned lat-

erally therefrom at its opposite ends and adapted to seat in said stem openings, and removable means for securing the locking member to the connecting barrel to prevent rotation of the latter relative to the screw members.

3. In combination with a turnbuckle comprising a central barrel having an aperture therethrough, screw stems threaded into opposite ends of said barrel and having openings therein at their outer portions, a locking member extending along said barrel and having opposite end portions seated in said screw openings, and a key mounted on said locking member and extending through said barrel aperture, for the purpose set forth.

4. In combination with a turnbuckle comprising a central barrel having an aperture therethrough, right and left hand screw stems threaded into opposite ends of said barrel, each having an eye or opening at its outer end, a locking wire extending along said barrel and having a hook portion at one end seated in one of said stem openings and a laterally turned portion at its opposite end seated in the opening of the opposite screw stem, and a cotter key having an eye for receiving said locking wire and a shank removably locked within said barrel aperture.

5. In combination with a turnbuckle comprising a barrel having a central aperture therethrough, right and left hand screw stems threaded into opposite ends of said barrel; one of said stems having an eye at its outer end and the other stem comprising a yoke head; a cotter key extending through said barrel aperture removably locked therein and having an eye at one end, a locking wire extending along the barrel through said key eye and having a hook at one end seated in the stem eye and a laterally turned portion at its opposite end inserted in said yoke, for the purpose set forth.

In testimony whereof I affix my signature.

ALBIN K. LONGREN.
